UNITED STATES PATENT OFFICE

ARTHUR D. VANDERGON, OF DELANO, MINNESOTA

TOY WINDMILL

Application filed June 6, 1931. Serial No. 542,605.

This invention relates to windmill toys and more particularly to toys of this type which are mounted for rotation upon a supporting spindle and which are provided with a front 5 propeller, a vane for holding the propeller in the face of the wind, and a jointed figure actuated by the movement of the propeller.

One of the chief features of objection to 10 toys of this type is based on the fact that the elements connected to the jointed figure for actuating the same have heretofore been exposed to the view of the observer. As a consequence, the effect intended to be produced by the moving jointed figure is distorted and 15 detracted from. Efforts have been made previously to conceal the operating mechanism by mounting it on one side or the other of the device but have proved entirely unsuccessful in the case of a windmill toy rotatably 20 mounted upon a supporting spindle inasmuch as the toy may be turned in any and all directions with changes in the direction of the wind. At best the arrangement could only be such that the operating mechanism is 25 concealed to observers in a specified area when the wind is blowing in a predetermined direction. It is exceedingly unpleasant to an observer to see the linkage system or other system 30 operating the jointed figure and one of the general objects of this invention is the provision of a simplified structure arranged in such a manner that no moving parts except those intended to be viewed by the observer are exposed regardless of wind direction or position of observer.

A further object of the invention is the provision of a simplified main housing and bearing structure within the housing for the reception of the supporting spindle, wherein 40 the bearing structure also serves to support and reinforce the relatively light main housing.

Still another object of the invention is the provision of a simplified structure wherein 45 the jointed figure is pivotally mounted upon an extension of the vane.

These and other objects of the invention will become more readily apparent upon a 50 detailed study of the drawing in conjunction with the specification and appended claims.

In the drawing, which is an illustration of the invention, Fig. 1 shows a side elevation of a windmill toy;

Fig. 2 is a vertical longitudinal cross-section through the structure shown in Fig. 1 55 with parts broken away;

Fig. 3 is a cross-section along the lines 3—3 of Fig. 2 and;

Fig. 4 is a plan view of the rear portion 60 of the main housing, the vane above the housing being shown in cross-section.

The numeral 2 designates a supporting spindle which may be secured in vertical position in any convenient manner as, for instance, on a fence post 4 by means of nails 65 6, and serves to support at its upper end the main housing 8 of the toy.

The main housing 8 is of box-like shape 70 with an open bottom and is preferably made of a blank of light sheet metal bent to form the top 10 and the sides 12. The top 10 has a projecting portion 14 at the rear which is bent at substantially 90 degrees as shown in Fig. 2 to form a closure for the rear end. The sides 12 are also provided with projecting flaps 16 and 18 which are folded across 75 at the same end, one above the other to reinforce the same so that the rear end wall of the main housing comprises the sheets 14, 16 and 18 constituting bent projections of the 80 top 10 and sides 12 respectively. The sheets 14, 16 and 18 are preferably held together by means of nuts and bolts passing therethrough. The front end wall 20 of the main housing comprises a blank of sheet metal 85 having bent edge portions 22 substantially at right angles thereto and lying adjacent the inner sides of the side walls 12. These bent edge portions 22 are preferably secured to the side walls 12 by means of nuts and 90 bolts as shown although rivets or soldering may be used throughout the housing structure if desired.

A vane 22 is secured to the rear of the main housing 8 in a plane substantially at 95 right angles to that of the top 10 and along the median line of the top. Preferably the vane 22 has a cut out portion conforming to the shape of the main housing 8 at the intersection of the top and rear end wall, and is 100

provided with integral flaps 24 on either side thereof engaging the top and integral flaps 26 on either side thereof engaging the end sheet 18 as shown in Fig. 4. The flaps 24 and 26 are preferably bolted to the housing in order to secure the vane in proper position.

A bearing ring 28 having a top and side walls shaped to conform generally to the 10 shape of the inner walls of the main housing is mounted therein with the top of the ring adjacent the top of the main housing and the sides of the ring adjacent the inner surfaces of the side walls 12. Bearing ring 28 15 is provided with a pair of oppositely disposed holes at the top and bottom respectively, which receive and form bearing surfaces for the supporting spindle 2. The ring may be secured to the walls of the main 20 housing in any convenient manner but it has been found advantageous to secure the top of the ring by means of a bent sheet metal member 30 as shown in Fig. 2 which may be soldered or otherwise connected to the inner 25 surface of the top 10. The sides of the ring are preferably connected to the main housing by means of nuts and bolts 32 passing through the side walls 12 and the sides of the ring. The upper flat portion of the sheet 30 metal plate 30 reinforces the top of the main housing opposite the supporting spindle and co-acts with the hole in the top of the bearing ring to form a thrust bearing, on which the main housing 8 is free to rotate about 35 spindle 2.

The top 10 is provided with a substantially rectangular opening formed by cutting the triangular portions 34 and bending them perpendicularly with respect to the top. Below 40 this opening there is formed within the main housing a chamber 36 having as end walls thereof, portions of the side walls 12, and having as side walls the plates 38 and 40 which may be mounted within the housing in 45 any convenient manner. Preferably the plates 38 and 40 are provided with bent edge portions engaging the sides 12 of the main housing and riveted or bolted thereto in a manner similar to the fastening of the bent 50 edge portions 22 of the front end 20. The chamber 36 is further subdivided into a compartment 42 formed of a bent U shaped sheet metal plate 44 having one leg of the U engaging the side wall 12 of the housing as shown 55 in Fig. 3. For the purpose of holding the member 44 in place a bolt 46 provided with a collar 48 having a length equal to the width of the inside of chamber 42 is provided. Upon fastening of the nut co-acting with the 60 bolt 46, the U shaped sheet metal plate 44 is held rigidly in position with its side edges adjacent the walls 38 and 40 and the bend of the U adjacent the top 10.

A drive shaft 50 which passes through 65 openings in the walls 38 and 40 is journalled

within the main housing and has a projecting portion 52 extending through the front end 20. Worm gear 54 which is fixed to this shaft, lies within the chamber 36 and preferably has a washer at each end to take up the play between the walls 38 and 40. The worm gear 54 meshes with a pinion 56 which is mounted on shaft 58 passing through the walls of the chamber 42 as shown in Fig. 3. The shaft 58 is provided with a collar 60 secured thereto by means of a set-screw and having ends forming a bearing surface with the inner walls of chamber 42 formed by the U shaped plate 44. Upon rotation of the propeller 62 which is secured to the projecting part of 52 of the drive shaft 50, the pinion 56 will be rotated by means of worm gear 54.

Positioned above the opening in the top of the main housing 8 is a secondary housing generally designated at 64 which is of rectangular cross-section and has pivoted therein a lever 66 to simulate a pump handle. The outer arm of the lever 66 is pivoted to a jointed figure designated at 68 which is mounted upon the front portion 70 of the vane 22 and the inner arm of lever 66 is connected to a link 72 which is eccentrically connected to the pinion 56. In order to further cause the secondary housing 64 and lever 66 to simulate a pump, a sheet metal plate 74 is provided in the outline of what would be the spout.

The vane 22 acts to hold the entire device in the direction of the wind, the main housing being capable of ready rotation about the spindle 2 by virtue of the bearing ring 28 which further serves to reinforce this housing. When the propeller is rotated by the wind and turns the drive shaft the pinion will be caused to rotate as previously explained, and the lever 66 will receive a rocking movement from the link 72. This rocking movement of the lever 66 will cause the jointed figure 68 to move up and down therewith to simulate the movements of a person operating the handle of the pump. It will be observed that all of the operating mechanism is concealed from the view of the observer irrespective of the relative position of the observer so that the proper and desired effect is at all times produced by the device.

Having described my invention, what I now claim as new and desire to secure by Letters Patent of the United States is as follows:

1. In a windmill toy, a supporting spindle, a main housing mounted for rotation upon said spindle and having a top provided with an opening therein, sides, and front and back ends, a vane mounted upon the housing and extended rearwardly therefrom in a plane substantially at right angles to the top, a jointed toy figure mounted above the said housing at a point removed from the opening therein, a drive shaft journalled in the hous- 125

- ing and projecting through its front end, a propeller secured to the projecting portion of the drive shaft, a pinion rotatably mounted in the housing below said opening in the top, 5 means for driving the pinion from said drive shaft, a secondary housing arranged over the aforesaid opening in the main housing, a lever pivoted in said secondary housing having one arm inside and the other projecting outside the secondary housing, the outside arm being pivotally connected to the jointed figure, and a link pivotally connected to said inside arm within the secondary housing and to the pinion, said secondary housing enclosing said link and being shaped to simulate with said lever a water 70 pump and handle. 75
4. A device as claimed in claim 2 wherein the jointed figure is pivoted to the vane. 80
- In witness whereof, I have hereunto set my hand this 4th day of June, 1931. 85
- ARTHUR D. VANDERGON. 90
2. In a windmill toy, a supporting spindle, a main housing mounted for rotation upon said spindle and having a top provided with an opening therein, sides, and front and back 20 ends, a vane mounted upon the housing and extended rearwardly therefrom in a plane substantially at right angles to the top, a jointed toy figure mounted above the said housing at a point removed from the opening 25 therein, a drive shaft journaled in the housing and projecting through its front end, a propeller secured to the projecting portion of the drive shaft, a secondary housing arranged over the aforesaid opening in the 30 main housing, a lever pivoted in said secondary housing having one arm inside and the other projecting outside the secondary housing, the outside arm being pivoted to the jointed figure and means connected to the 35 inside arm of the lever for rocking the same upon rotation of the drive shaft, said rocking means being enclosed within the main and secondary housings. 40
3. In a windmill toy, a supporting spindle, a main housing having a top provided with an opening therein, sides, and front and back 45 ends, a bearing ring having a top and sides conforming substantially to the contour of the top and sides of the main housing, said ring being mounted within said housing with its top and sides adjacent to the top and side walls of the housing to reinforce the same, said bearing ring being provided with oppositely disposed upper and lower openings for 50 the reception of the supporting spindle whereby said housing may be rotatably mounted upon the top of said spindle, a vane mounted upon the housing and extending rearwardly therefrom in a plane substantially at right 55 angles to the top, a jointed toy figure mounted above the housing at a point removed from said opening therein, a drive shaft journaled in the housing and projecting from the front end thereof, a propeller secured to the projecting portion of the drive shaft, a pinion rotatably mounted in the housing opposite said opening in the top, means for driving the pinion from said drive shaft, a secondary 60 housing arranged over the aforesaid opening and having a longitudinal axis substan- 65
